US00D809190S

(12) **United States Design Patent** (10) Patent No.: **US D809,190 S**
(45) Date of Patent: ** Jan. 30, 2018

(54) **VAPORIZER**

(71) Applicant: **NJOY, LLC**, Scottsdale, AZ (US)

(72) Inventors: **David Schuler**, Scottsdale, AZ (US);
Ryan Miller, Scottsdale, AZ (US)

(73) Assignee: **NJOY, LLC**, Scottsdale, AZ (US)

(**) Term: **15 Years**

(21) Appl. No.: **29/533,000**

(22) Filed: **Jul. 13, 2015**

(51) LOC (11) Cl. **27-01**

(52) U.S. Cl.

USPC **D27/101**
